UNITED STATES PATENT OFFICE.

GEORGE J. FALLESEN AND WALTER L. FARLEY, OF ROCHESTER, NEW YORK, ASSIGNEES
TO EASTMAN KODAK COMPANY, OF ROCHESTER, NEW YORK, A CORPORATION OF
NEW YORK.

ROLL AND FASTENING MEANS THEREFOR.

1,332,890.

Specification of Letters Patent. Patented Mar. 9, 1920.

Application filed November 7, 1917. Serial No. 200,692.

To all whom it may concern:

Be it known that we, GEORGE J. FALLESEN and WALTER L. FARLEY, citizens of the United States of America, residing at Rochester, in the county of Monroe and State of New York, have invented certain new and useful Improvements in Rolls and Fastening Means Therefor, of which the following is a full, clear, and exact specification.

10 This invention relates to means for fastening rolls of sheet material to prevent unwinding. More particularly it relates to improvements in adhesive-bearing fastening strips, such, for example, as are used on photographic roll-film cartridges and are known in the art as "pasters" or "sticker-bands".

One object of this invention is to keep the fastening strip in convenient position and proper condition until used. Another object is to prevent premature adhesion of the fastening strip. Still another object is to provide a fastening strip that will not crack when normally folded. A further object is to provide a strip which may be used to fasten rolls of paper which are resistant to adhesive. Yet another object is to conveniently locate such a fastening strip in a photographic cartridge and on that end of the film-supporting leading-strip or backing-strip, which will be on the outside of the roll when the latter is removed from a camera after exposure. A still further object is to so locate the fastening strip near the end of the lead strip of a photographic film element that it will be conveniently accessible yet will not interfere with the insertion of the lead strip in the slot of a winding spool but will, in a measure, reinforce the end of the lead strip. Other objects will hereinafter appear.

15 Since this invention is particularly satisfactory when used in photographic film cartridges, we shall describe its embodiment in such a cartridge by way of illustration. It will be, of course, understood that the invention is not confined to this particular example but is capable of other forms within the scope of the claims.

In the accompanying drawing Figure 1 is 20 a side elevation of a film cartridge in which our invention is embodied, the roll being fastened.

Fig. 2 is a cross section taken upon the line 2-2 of Fig. 1.

Fig. 3 is a transverse cross section on a 55 larger scale than Fig. 2 and showing the parts prior to fastening the roll and indicating the relation of the backing paper and fastening strip when the latter is folded.

Fig. 4 is a perspective view with the end 60 of the backing paper partly unrolled to show the folded end of the fastening strip.

Fig. 5 is a perspective view showing the parts in an intermediate stage of manipulation with the free end of the fastening strip 65 in extended position.

Fig. 6 is a central transverse section showing the parts in the same relative position as Fig. 5.

Fig. 7 is a detailed view of the fastening 70 strip.

Fig. 8 is a detailed view of a modification.

Figs. 9, 10 and 11 are sectional views of the film strip with its accompanying papers in unrolled condition, these several figures illustrating different well known arrangements. 75

The film spool shown in the accompanying drawing is of the conventional type comprising a hub 1 and the end flanges 2. To this hub there is fastened the inner end of a strip or sheet 3 of paper of suitable opacity and having special adhesive resisting features which will be hereinafter referred to. It is wound upon the spool in a series of convolutions, as indicated in Figs. 2, 3, and 6. Intermediate the ends of this strip there is attached in any of the known or preferred ways a band of photographically sensitive film of the conventional type; thus the film 10 may be backed by the paper throughout 80 its length, as shown in Figs. 9 and 10 or the ends of the film 10 may be joined to sections 3', 3'' of the paper strip. Also, carbon paper 12 or other strips may be operatively associated with the film as shown in Fig. 9. All 85 of these structures are well known in the art. The usual stickers 13 and 14 for attaching the film to the backing sheet are shown. 90

The roll is fastened in its coiled position by a strip designated generally by S. This 100 strip is attached in the preferred form at 6 to the outer end of the sheet 3. On the inner face of the free portion 7 there is located an adhesive area or portion 9 which, when the end 7 is bent at 8 over the end of sheet 3, will 105 be brought into contact with the area on the inner face of said sheet, as indicated in Figs. 3 and 4. The parts being wound up after

being in the position shown in Figs. 3 and 4, the adhesive portion of the strip S will be stored between the outer convolutions of the sheet or backing strip 3. As most clearly indicated in Fig. 4, the end of the sheet 3 is shaped at 4 so as to conveniently enter the slot of a winding spool and, since the parts 6 and 7 of the strip S are folded to lie against the faces of the sheet they will not interfere with the introduction of the end of sheet 3 into the slot, but will rather act to reinforce such end and help it to withstand the initial winding stresses.

The strip S is preferably and normally located upon that end of the sheet or backing strip 3 which is on the outside of the roll after the film has been exposed in the camera and removed therefrom. In the case where sheet 3 and its associated film parts are wound entirely off the supply spool and completely onto the winding spool, the strip S will be located in the slot of the supply spool at the start and will be on the outside of the winding spool at the end of the operation in the position indicated in Figs. 3 and 4. If the film, however, be used in a camera in which the sheet or strip 3 and its film parts are drawn onto the winding roller and then rewound back upon the supply spool, as in certain types of panoramic cameras, then the strip S will be both initially and finally located upon the outer end of the strip 3, as shown in Figs. 3 and 4. It will be threaded into the slot of the winding roller together with the end of strip 3 during the loading of the camera and will be removed from such slot at the end of the rewinding operation.

Thus, in any event, the cartridge will have the strip S accessible for manipulation when it is removed from the camera. To fasten the roll, the free end 7 of strip S is turned outwardly from the position shown in Figs. 3 and 4 to the position shown in Figs. 5 and 6, straightening out the folded portion 8 and conveniently locating the adhesive portion or area 9 for moistening or other preparatory treatment. After such treatment, the strip is wound around the roll and the adhesive portion 9 stuck down. Preferably the strip S is of greater length than the outermost convolution of the roll so that its ends will overlap and the area 9 will adhere to the portion 6, the roll being encircled and held by the latter, as indicated in Figs. 1 and 2.

In this preferred form of our invention the strip S bears the adhesive area or portion 9 at its outer end so that the portion 8, which is folded, will be normally free from the usually brittle adhesive and hence the danger of cracking or weakening the strip S at the portion 8 will be avoided. With some forms of adhesive this precaution may not be necessary and we have therefore illus-

trated in Fig. 8 a modification in which the whole inner face of the free end of strip S is coated with suitable adhesive 11.

The adhesive 9, prior to use in the camera, is stored in the cartridge between convolutions of sheet 3, as stated above. Unless some provision be made to avoid it, the adhesive may become prematurely fastened to the inner face of sheet 3, especially in hot or humid climates. When the operator attempts to fasten his roll, such a premature adhesion will prevent the hereinabove described attaching operation. It is an important part of our invention that we reduce the possibility of this trouble to a minimum. To that end, we make the area of sheet 3 which covers the adhesive 9 and against which it is stored, resistant to the adhesive, even when the latter is moist. By resistant we mean that the adhesive when manipulated in the normally intended way by the operator will not reliably stick or adhere to the surface or area. This adhesive resisting area against which the adhesive portion 9 is stored is most easily obtained when the entire sheet 3 is composed of resistant material. For example, if sheet 3 be made of so-called waterproof paper, it will be resistant to adhesive portion 9 when the latter is composed of the ordinary adhesives customarily used on the pasters or sticker bands employed at present in the art.

While we prefer to use an entire sheet of material that is adhesive-resistant on both sides, our invention is, of course, not limited to such a form and the paper may be of the kind in which the inner surface only, or even a portion of such inner surface, is made adhesive resistant, the important point being that adhesive portion 9 rests against a suitably resistant area.

While the adhesive portion 9 is normally dry until ready for use, it is not necessarily so, but may be more or less tacky or moist without harm. While we prefer to attach the strip S to the outer side of the end of sheet 3, we do not wish to be limited to such attachment except as specified in the accompanying claims, our invention comprising in its broader aspect the employment of a strip even where the portion 6 thereof is not initially fastened to the sheet 3. Where the portion 6 of strip S is attached to sheet 3, any preferred mode may be employed. A special adhesive toward which sheet 3 is not resistant may be used or the adhesive used in attaching portion 6 to sheet 3 may be the same adhesive that is employed in portion 9 and toward which said sheet is normally resistant, the adhesive on portion 6 being given an abnormal or special treatment to make it adhere to the strip. It is furthermore noted that the attachment of portion 6 to the end of sheet 3 is chiefly a convenience during storage and it is not subject to as

great stresses as those which pull on the strip when the latter is used to fasten the roll. Consequently a union or adhesion which would be unreliable and impracticable when fastening the roll will be entirely satisfactory for holding portion 6 to sheet 3 during storage. In the preferred embodiment of our invention we make use of this fact and the adhesive area 10, which holds portion 6 to sheet 3, is of the same substance as the adhesive in area 9.

While in the preferred form of our invention strip S is of sufficient length to encircle the roll and be fastened by an overlapping adhesive joint, it will be understood that within the scope of our invention, the strip S may be of shorter length and the adhesive 9 may be stuck to one of the outer convolutions of the sheet 3 wherever the outer face 20 of sheet 3 is less adhesive-resisting than the inner face thereof.

Having thus described our invention what we claim as new and desire to secure by Letters Patent is:

25 1. An article of manufacture comprising a roll of flexible material resistant to an adhesive and a flexible fastening strip for the roll, said strip bearing a portion coated with an adhesive with respect to which the 30 material of the roll is resistant, said adhesive being stored between convolutions of the roll.

2. A photographic film cartridge comprising a spool, a flexible sheet wound on the 35 spool and carrying a film, the sheet being resistant to an adhesive, and a fastening strip, said strip having a portion coated with an adhesive toward which the sheet is resistant, said adhesive being stored between convolutions of the sheet and covered thereby.

3. In combination, a sheet of flexible material adapted to be wound into a roll, said sheet having an adhesive-resisting area, and a flexible fastening strip, one end of said 45 fastening strip being attached to the sheet and the other end being free, said free end bearing an adhesive portion, said adhesive portion and said adhesive-resisting area being relatively movable into contact to cover 50 said adhesive portion and out of contact to manipulate said adhesive portion in fastening the roll.

4. A photographic element adapted to be wound into a roll comprising a flexible sheet carrying a film strip on its inner side, at 55 least a portion of said inner side of said sheet being adhesive-resisting, a flexible fastening strip having one of its ends attached near an end of the sheet, the other end of the

fastening strip being free and bearing an 60 adhesive portion movable into position in contact with said inner side of the backing sheet or outwardly for fastening the roll.

5. In combination a sheet of flexible material adapted to be wound into a roll, said 65 sheet having an adhesive-resisting area, and a flexible fastening strip, one end of which is attached near an end of the sheet, the unattached portion of the fastening strip bearing an adhesive area and being folded to 70 bring the adhesive area into contact with said adhesive-resisting area of the sheet, said fastening strip being free from adhesive at the fold.

6. In combination a sheet of flexible material adapted to be wound into a roll, said sheet having an adhesive-resisting area, and a flexible fastening strip having greater length than the outer convolution of said roll, one end of said strip being attached to 80 the sheet and the other end thereof bearing an adhesive portion, said adhesive portion and said adhesive-resisting area being relatively movable into contact to cover said adhesive portion and out of contact to 85 bring the fastening strip around said roll, with the adhesive portion overlapping said attached end of the fastening strip.

7. A photographic film cartridge, comprising a spool, a flexible sheet wound on the spool and carrying a film, at least the inner side of the sheet being adhesive-resisting, a fastening strip attached to the end of the sheet which is outmost after use in the camera, said strip having a free portion 90 bearing adhesive and being movable to bring the adhesive into protective contact with said inner side of the sheet and out of contact to permit manipulation of said adhesive in fastening the roll.

8. A photographic element for co-operation with a slotted winding spool, comprising a film having attached thereto a leading sheet which is surfaced to be adhesive-resisting, the free end thereof being shaped to enter the slot of a winding spool, and a fastening strip, one end of which is attached to said free end of the sheet, the free part of said strip bearing an adhesive area and being foldable over said free end of the 105 sheet to bring the adhesive area into protective contact with said sheet and adapt the free end of the sheet and the strip to enter said slot.

Signed at Rochester, New York, this 29 115 day of October 1917.

GEORGE J. FALLESEN.
WALTER L. FARLEY.
